UNITED STATES PATENT OFFICE.

HERMAN A. FINKE, OF ST. LOUIS, MISSOURI.

CARBURETOR.

Application filed November 24, 1926. Serial No. 150,575.

This invention relates to carburetors for internal combustion engines and has for its object to provide a device simple in construction and more efficient in operation than those heretofore proposed.

With these and other objects in view the invention consists in the novel details of construction and arrangements of parts as will be more fully hereinafter disclosed and particularly pointed out in the claims.

Referring to the accompanying drawings forming a part of this specification in which like numerals designate like parts in all the views—

15 Fig. 1 is a vertical sectional view of the device;

Fig. 2 is a transverse sectional view taken as on the line 2—2 of Fig. 1 and looking in the direction of the arrows;

20 Fig. 3 is a fragmentary view partly in section illustrating the control of the atomizing passages for the liquid fuel; and

Fig. 4 is a detail view partly in section illustrating a modified form of fuel valve 25 actuating mechanism.

In order that this invention may be more properly understood it is said that heretofore, in carburetor construction, there has been little, if any attention given to the accurate control of the ratio of liquid fuel to air admitted to the intake manifold of the engine. This invention, on the other hand, is directed to the supply of known quantities of liquid fuel, with the result that the ratio of the fuel and the air is definitely maintained. Also this invention is directed to the admission of the liquid fuel by force to the air chamber of the carburetor and further, the means for determining the quantity of air admitted to the carburetor also controls the amount of liquid fuel admitted to the air chamber.

In the drawings 1 generally indicates a cylinder provided at one end with a head 2 centrally apertured as at 3, and having formed therein a fuel chamber 4 adjacent said aperture and communicating with the interior of the cylinder 1 on one side as by the small aperture 5. This aperture has associated therewith a ball 6 which is pressed as by the spring 7 against the aperture to normally close the same. The other end of the spring 7 is adapted to be retained in proper place in the chamber 4 by a pin 8 formed on the inner end of a plug 9 threaded

into the end of the head 2 of the cylinder 1 as clearly shown, said plug adapted to form an abutting surface for said end of the spring 7.

Associated with the fuel chamber 4 is the group of minute apertures passing through the outer wall thereof to the outside of the cylinder 1, said group comprising an aperture 15 substantially centrally disposed of said chamber 4 and substantially radially disposed of said cylinder. This aperture 15 is flanked on one side by an aperture 16, likewise of minute diameter, but having its axis angularly disposed to the axis of the aperture 15. The aperture 17, also of minute diameter, flanks the aperture 15 on its other side and its axis is also angularly disposed to the axis of the aperture 15. With particular reference to Fig. 1, it will be seen that the axis of each of the apertures 16 and 17 lies in a transverse plane of the cylinder 1 which is angularly disposed to a right transverse plane of said cylinder. With particular reference to Fig. 2 it will be seen that the axis of each of the apertures 16 and 17 lies in a longitudinal plane of the cylinder not passing through the axis thereof. And with particular reference to Fig. 3 it will be seen that the outlets of the apertures 15, 16 and 17 on the outer cylindrical surface, lie in a common oblique transverse plane of the cylinder 1. Thus it may be said that the axis of each aperture 16 and 17 lies in a plane angularly disposed to both a central longitudinal and a right transverse plane of the cylinder. It is to be understood, however, that the three apertures 15, 16 and 17 are merely taken by way of example, as with engines of various sizes a greater or lesser number of apertures may be found most efficient. But in any instance, the apertures are so provided that the fuel will be atomized in sprays directed across the air chamber to be described later.

The other end of the cylinder 1 is unobstructed and adapted to slidably receive a cylindrical sleeve 20, the inner end of which is unobstructed but the outer end of which is provided with an annular flange 21 forming a seat for one end of a coil spring 22 the other end of which is adapted to rest and operate on the head 23 of a piston 24 adapted to slidably engage the inner surface of the sleeve 20. This piston

90

95

100

105

110

24 is of hollow cylindrical shape, as clearly shown in Fig. 1, the inner cylindrical surface adapted to slidingly receive a hollow cylindrical plunger 25 provided with the head 26 at one end having integrally formed therewith the stem 27 adapted to slidingly engage the aperture 3 provided therefor in the head 2 of the cylinder 1. The open end of the piston 24 is internally screw threaded 10 to receive a ring or annular shoulder adapted to serve as a seat for one end of the coil spring 29, surrounding the stem 27, the other end of said spring taking against the inner surface of the head 2 of the cylinder 1.

15 The shouldered end of the sleeve 20 is provided with a yoke construction or bracket 35 extending away from said sleeve, forming a support for the pin or shaft 36 on which is freely mounted the contact roller 37 adapted to be engaged by a cam 38 mounted on a shaft 39 receiving power in any well known manner, not shown, from the engine. The head 23 of the piston 24 is provided with an outwardly disposed central extension 45 constituting a bracket for supporting a pin 46 on which is freely mounted a contact roller 47 adapted at times to be engaged by the roller 37 carried by the sleeve 20.

30 From the above description and with particular reference to Fig. 1 it will be seen that upon the rotation of the shaft 39, the cam 38 rigid therewith will cause the sleeve 20 to be moved within the cylinder 1 through the medium of the roller 37 and bracket 35. In this movement tension will be placed upon the spring 22 and, therethrough, pressure applied to the head 23 of the piston 24, causing the latter to move inwardly with respect to the cylinder 1. During this movement of the piston 24 there will be a tendency to move the plunger 25 therewith which, however, will be thwarted by the spring 29 disposed at the innermost end of the cylinder 1. However, the piston 24 continues in its movement and thus it will be seen that, due to the tight sliding engagement between said piston 24 and the plunger 25, there is created an air cushion.

40 A reversal of movement of the parts will take place as the cam 38 recedes from the roller 37 due to the springs 22 and 29, or in other words, the sleeve 20 will travel outwardly of the cylinder 1, and in this movement will release the tension on the spring 22 allowing the piston 24 to likewise move outwardly with respect to said cylinder, this last named movement being assisted by the spring 29 heretofore under tension.

55 The closed end of the cylinder 1 is rigidly mounted in an aperture therefor contained in a valve plate 50 which constitutes one side of a circular air chamber 51, the entire air chamber being provided with suitable flanges such as 52 by which the chamber

may be secured to the intake manifold of the engine generally indicated by the dot and dash line 53. In other words, the air chamber 51 is of circular box formation having at its central portion the cylinder 1 70 projecting therein, and at its circumference, and between the flanges 52, an outlet 54 through which the air may pass to the intake manifold. The chamber 51 is provided with a removable cover plate 55 secured as 75 by the screws 56 to lugs 57 formed on the circular wall 58 of said chamber. The cover plate 55 is disposed in a plane substantially parallel with the valve plate 50 as clearly shown in Fig. 1.

80 Fitting between the valve plate 50 and the cover 55 of the air chamber, there is disposed the air valve 60 which has a circular plate base 61 from which centrally extends a hub portion 62 recessed as at 63 to tightly but revolvably fit over the head 2 of the cylinder 1 extending into the air chamber. This hub portion 62 is provided with an aperture in its side wall of substantially rectangular shape as clearly indicated at 85 64 see Fig. 3, providing a passage adapted to register with the atomizing apertures 15, 16 and 17 formed in the cylindrical wall of the cylinder 1 and communicating with the fuel chamber 4. The valve structure 60 is adapted to be rotated about the end of the cylinder 1 as by a lever 70 secured to the base plate 61 as by the bolts 71, said bolts adapted to pass through a circular opening 72 provided in the valve plate 50. Besides this opening 72, the plate 50 is provided with similar openings 73 and 74 disposed on opposite sides of the opening 72 and at equal spacing therefrom as clearly indicated in Fig. 2. Adapted to register with these openings 72, 73 and 74 are the openings 75, 76 and 77 in the base plate 61 of the air valve 60. That is to say, when the lever 70 is operated from any convenient point, the air valve 60 may be rotated so that a fraction of, or all of, the openings 75, 76 and 77 will register with the openings 72, 73 and 74 for the passage of air therethrough into the air chamber 51 from which it will subsequently be drawn through the outlet 54 into the intake manifold of the engine due to the vacuum created by the pistons of the engine.

100 From what has been above disclosed it will be evident that liquid fuel under pressure from any suitable source, not shown, may be conducted to this carburetor as through the pipe 80 and passed through the orifice 81 in the side of the cylinder 1 into 105 said cylinder to occupy the space generally indicated by the numeral 82 and which may be referred to as the fuel reservoir. Upon operating the cam 38, the sleeve 20 will be moved inwardly of the cylinder 1 and in this connection it is to be particularly observed 110

70

from Fig. 1 that the innermost end of the sleeve 20 is so positioned that upon movement of said sleeve by the cam, the end of the sleeve will pass across and close the 5 aperture 81 through which the liquid fuel is admitted to the fuel reservoir 82. By this action, the fuel is trapped in the reservoir 82 and held in reserve subject to the subsequent pressure caused when the sleeve 10 roller 37 contacts with and moves the piston roller 47, causing the piston assembly to move against the fuel in said reservoir and to force the fuel into the charging pocket or fuel chamber 4 through the valved opening 5. That is to say, the sleeve 20, piston 24 and plunger 25 all cooperate to put pressure upon said fuel, and any additional pressure will cause said fuel to be atomized through the minute apertures 15, 16 and 17 20 into the air chamber 51, the ball valve 6 preventing any return of the fuel back through the said orifice 5. It has been found that the best results are obtained when the liquid fuel is ejected through orifices of the approximate diameter of 4/1000 of an inch, at substantially one pound pressure. In other words, the cylinder 1, sleeve 20, piston 24, plunger 25, fuel reservoir 82, fuel chamber 4, and associated parts are all 25 of such dimensions as will cause a pressure of one pound to be exerted on the fuel passing through the atomizing apertures 15, 16 and 17 through the medium of the cam 38.

30 The fuel passed through the apertures 15, 16 and 17 will be atomized into the air chamber 51, and with particular reference to Figures 1 and 2 it will be observed that the fuel atomized through the aperture 16 will 35 be in a direction across the path of the fuel atomized through the apertures 15 and 17. The purpose of so disposing the apertures 15, 16 and 17 as heretofore described is to cause the fluid fuel in its atomized condition 40 to fill a larger area of the air chamber 51 than if the apertures were in different positions. It is also to be observed that these apertures are so arranged as to direct the atomized fluid toward the outlet passage 45 54 so that the air which enter the chamber 51 through any of the ports 72, 73, and 74 will pick up the fuel in its atomized state and mix therewith in a thorough manner before the mixture reaches the intake manifold of the engine.

55 The amount of liquid fuel admitted to the air chamber 51 is controlled in accordance with the amount of air admitted to the chamber 51. That is to say, and with particular reference to Fig. 2 it will be seen from the position of parts that all of the apertures 15, 16 and 17 are covered by the cylindrical wall of the hub portion 62 of the air valve 60, and further that when these 60 apertures are so covered, the air ports 72,

73 and 74 are also covered by the plate member 61 of the air valve. With the parts in this position it will therefore be evident that neither air nor liquid fuel can enter the air chamber 51.

75 However, when the lever 70 is actuated to move the air valve, the hub portion will also be moved to uncover first the aperture 16, then the aperture 15, and then the aperture 17, there being provided the large opening 64 (see Fig. 3) in the hub portion of the air valve so that all three of the fuel apertures can remain uncovered at the same time. Further, this opening 64 is of such circumferential dimension that these three 80 fuel apertures will remain in an open position even when the lever 70 has been moved to its dotted line position as seen in Fig. 2, when the greatest amount of air will be permitted to enter the chamber 51. Any 85 suitable means for limiting the extent to which the air valve 60 may be moved may be provided, but in the drawings recesses 90 have been illustrated to receive the bolts 91 connecting the air valve with its operating lever 70, the recesses 90 being provided in the circumferential limits of one of the air ports in the air chamber 51 such as 72.

90 In the above description the operation of the sleeve member 20 has been described 95 as being actuated by a cam 38, but any other suitable means may be employed within the scope of this invention, such as a bell crank pivoted as at 91 to a bracket 92 secured to the engine, and provided with one arm 93 100 adapted to engage the contact roller 37 carried by the bracket 35 rigidly mounted on the sleeve 20, and the other arm 94 provided at its extremity with a connecting link 95 adapted to be operated automatically by 105 the engine at the same or similar timing as the cam 38 illustrated in Fig. 4.

110 From the foregoing description it will thus be seen that by this device a measured quantity of air is admitted to the air chamber 51, and at the same time a measured quantity of liquid fuel is injected into said air chamber, the control of both being through the medium of the throttle lever 70 and the air valve 60. As the supply of 115 liquid fuel is increased, so also is the amount of air increased through the normal operation of the device. Also it is to be observed that the liquid fuel is sprayed or atomized into the mixing chamber 61 in diagonal directions to compel contact with substantially all of the air passing through the outlet 54 from the air chamber 51 with the natural result of a higher degree of saturation than would be obtained were the minute apertures 15, 16 and 17 not so arranged as to cause the liquid fuel to be sprayed in different directions.

120 With particular reference to Fig. 1 it is to be observed that when the cam 38 slowly 125

rotates about the shaft 39, it will actuate the contact roller 37 carried by the sleeve 20 causing the latter to move inwardly of the cylinder 1 with a simultaneous compression 5 of the spring 22. The spring 22 upon being compressed tends to force the piston 24 likewise inwardly of the cylinder 1, and this movement of the piston 24 is further caused by the subsequent contacting of the roller 10 37 with the roller 47 carried by said piston. In other words, there is considerable surface or skin friction between the outer surface of the piston 34 and the inner surface of the sleeve 20, and also between the outer 15 surface of the sleeve 20 and the inner surface of the cylinder 1. The inward movement of the piston 24 is counteracted by the spring 29 disposed at the other end thereof so that the spring 22 will be positively compressed 20 to facilitate the separation of the rollers 37 and 47 on release of the pressure by the cam 38. The plunger 25 disposed within the piston 24 likewise is adapted to have a tight surface or skin friction with relation to the 25 inner surface of said piston, but it is to be observed that no spring action controls said plunger. On the other hand, the stem 27 of said plunger passes freely through the central portion of the helical spring 29 and 30 into the aperture 3 provided therefor in the head 2 of the cylinder 1. That is to say, the plunger 25 is not mechanically restricted in its movement relative to the piston 24, but it has relative movement due to the 35 pressure exerted thereon by the liquid fuel in reservoir 82. As stated above, when the cam 38 slowly rotates, the parts of the carburetor will move as described, the piston 24 carrying therewith the plunger 25. The 40 supply of liquid fuel will be cut off by the unobstructed end of the sleeve 20 and what fuel is in the reservoir 82 will be forced through the opening 5 into the fuel chamber 4 and out through the minute apertures 15, 45 16 and 17 by a piston movement. the piston comprising the unobstructed ends of the sleeve 20, of the piston 24 and the solid head 26 of the plunger 25. The rotation of the cam 38 being relatively slow, the liquid fuel 50 will be given opportunity to leave the reservoir 82, pass through the fuel chamber 4 and be atomized into the air chamber 51, all as will be evident and readily understood. Upon the rapid rotation of the cam 38, the 55 liquid fuel will offer a greater resistance due to the incompressibility of the said liquid and therefore the plunger 25 will move slightly within the piston 24, compressing the air within the hollow plunger 25 and said piston so that less liquid fuel 60 will be automatically atomized through the apertures 15, 16 and 17, which also will be evident and readily understood. Upon subsequent decrease of the revolution of the cam 38, the air under compression within the

plunger of the piston will force the former out of the latter to its normal position as shown in Fig. 1.

Thus it will be seen that the supply of liquid fuel to the air chamber 51 is not only automatically controlled through the operation of the lever 70 controlling the amount of air admitted to said chamber, but it is also controlled by the speed of rotation of the cam shaft 39 so that too much liquid fuel will never be admitted to the air chamber 51. By such a construction "back-fires" are substantially if not completely eliminated in the engine from preignition as are now caused by present known constructions. Should any back-fire be produced in the carburetor of this invention, said back-fire would not produce damaging results because there would be no needle valves to be dislodged or put into a "stuck" position with resultant flooding of the intake manifold with liquid fuel. Further, a carburetor of this character would be impossible of catching fire due to the minute size of the apertures 15, 16 and 17 which would effectively stop any blaze from going therethrough to ignite or explode the gasoline or other combustible fluid used as fuel in the chamber 4, and the ball valve 6 would prevent the force of any back-fire having any effect upon the assembly 90 of the carburetor itself.

From the foregoing it will therefore be seen that by this invention there is provided a carburetor for internal combustion engines having in combination reciprocating spring 100 controlled means including the sleeve 20, the piston 24 and the springs 22 and 29 for forcibly supplying a known quantity of liquid fuel to the mixing chamber 51; with means circumjacent the fluid forcing 105 means for compressing the apertured wall 50 of the mixing chamber 51 for supplying a known quantity of air to said mixing chamber. Also in combination with the above is the rotatable common contact means comprising the member 60 having the apertured plate portion 61 and the circumferential aperture 64 to control the supply of fuel and air to the mixing chamber 51, the circumferential aperture 64 coacting with the atomizing apertures 15, 16 and 17 and the apertured plate 61 coacting with the apertured wall 50 of the mixing chamber. And 110 lastly there is provided in combination with the above, yieldable air and fluid pressure 115 actuated means comprising a movable wall (the head 26 of the plunger 25) including an air compression chamber (within the plunger 25 and within the piston 24) to regulate the supply of fuel, governed by the back pressure on said fuel, and in accordance with the speed of the engine. That is to say, upon the faster reciprocation of the sleeve 20 and its associated piston 24 and plunger 25, the solid head 26 of the plunger 120 will be unable to force the liquid fuel from 125 130

the reservoir 82 through the spring ball controlled aperture 5, through the fuel chamber 4 and out through the apertures 15, 16 and 17 fast enough, so that the inherent incompressibility of the fluid will cause the head of said plunger 25 to be moved inwardly with respect to its piston wall 24, compressing the air in the hollow of the piston and plunger. However, on the movement of the 10 sleeve 20 and its associated parts, outward with respect to the cylinder of the carburetor 1, the air under compression within the piston and plunger, will force the plunger outwardly with respect to the piston 24 with the result that the plunger will be ready in 15 its substantially normal position as shown in Fig. 1 when the cam 38 next moves the parts inwardly of the cylinder 1.

It is obvious that those skilled in the art 20 may vary the details of construction as well as arrangements of parts without departing from the spirit of the invention, therefore it is not desired to be limited to the foregoing disclosure except as may be required by the 25 claims.

What is claimed is:—

1. In a carburetor for internal combustion engines the combination of means to forcibly supply a known quantity of liquid 30 fuel to a mixing chamber; means to supply variable quantities of air to said mixing chamber; common means to control the supply of fuel and air to said chamber; and fluid pressure operated means to regulate the 35 supply of fuel in accordance with the speed of the engine.

2. In a carburetor for internal combustion engines the combination of reciprocating means to forcibly supply variable quantities of liquid fuel to a mixing chamber; means to supply a known quantity of air to 40 said mixing chamber; rotatable common means to control the supply of fuel and air to said chamber; and yieldable fluid pressure operated means to regulate the supply 45 of fuel in accordance with the speed of the engine.

3. In a carburetor for internal combustion engines the combination of means to forcibly supply a known quantity of liquid fuel to a mixing chamber; means to supply variable quantities of air to said mixing chamber; common means to control the supply of fuel and air to said chamber; and means comprising a movable wall to regulate the supply 55 of fuel in accordance with the speed of the engine.

4. In a carburetor for internal combustion engines the combination of means to forcibly supply a known quantity of liquid fuel to a mixing chamber; means to supply variable quantities of air to said mixing chamber; common means to control the supply of fuel and air to said chamber; and means to regulate the supply of fuel governed by the pres-

sure thereon and in accordance with the speed of the engine.

5. In a carburetor for internal combustion engines the combination of means to forcibly supply a known quantity of liquid 70 fuel to a mixing chamber; means to supply variable quantities of air to said mixing chamber; common means to control the supply of fuel and air to said chamber; and air and fluid pressure actuated means to 75 regulate the supply of fuel in accordance with the speed of the engine.

6. In a carburetor for internal combustion engines the combination of reciprocating spring controlled means to forcibly supply a known quantity of liquid fuel to a mixing chamber; means circumjacent said last named means to supply variable quantities of air to said mixing chamber; common contact means to control the supply of 80 fuel and air to said chamber; and means including an air compression chamber to regulate the supply of fuel in accordance with 85 the speed of the engine.

7. In a carburetor of the character described the combination of a reservoir to receive a liquid fuel; reciprocating means to cut-off the fuel supply to said reservoir; a fuel chamber associated with said reservoir to receive the fuel therefrom; means to force the fuel from said reservoir into said chamber; means to prevent a back flow of said fuel from said chamber; a mixing chamber; means to vary the quantity of air admitted to said mixing chamber; means associated with said fuel chamber and controlled by said last named means to cause varying quantities of fuel to be atomized into said mixing chamber; and means to vary the quantity of fuel supplied to said 95 fuel chamber in accordance with the rate of travel of the reciprocating cut-off means. 100

8. In a carburetor of the character described the combination of a reservoir to receive a liquid fuel; reciprocating means to 110 cut-off the fuel supply to said reservoir; a fuel chamber associated with said reservoir to receive the fuel therefrom; means to force the fuel from said reservoir into said chamber; means to prevent a back flow of said fuel from said chamber; a mixing chamber; means to vary the quantity of air admitted to said mixing chamber; means associated with said fuel chamber and controlled by said fuel chamber and controlled by said 115 last named means to cause varying quantities of fuel to be atomized into said mixing chamber; and fluid pressure operated means to vary the quantity of fuel supplied to said fuel chamber in accordance with the rate of travel of the reciprocating cut-off means. 120

9. In a carburetor of the character described the combination of a reservoir to receive a liquid fuel; reciprocating means to 130

cut-off the fuel supply to said reservoir; a fuel chamber associated with said reservoir to receive the fuel therefrom; means to force the fuel from said reservoir into said chamber; means to prevent a back flow of said fuel from said chamber; a mixing chamber; means to vary the quantity of air admitted to said mixing chamber; means associated with said fuel chamber and controlled by said last-named means to cause varying quantities of fuel to be atomized into said mixing chamber; and means comprising an air and fluid pressure actuated movable wall to vary the quantity of fuel supplied to said fuel chamber in accordance with the rate of travel of the reciprocating cut-off means. 10. In a carburetor of the character described the combination of a reservoir to receive a liquid fuel; reciprocating means to cut-off the fuel supply to said reservoir; a fuel chamber associated with said reservoir to receive the fuel therefrom; means to force the fuel from said reservoir into said chamber; means to prevent a back flow of said fuel from said chamber; a mixing chamber; means to vary the quantity of air admitted to said mixing chamber; means associated with said fuel chamber and controlled by said last named means to cause varying quantities of fuel to be atomized into said mixing chamber; and automatic yieldable pressure means to vary the quantity of fuel supplied to said fuel chamber in accordance with the rate of travel of the reciprocating cut-off means. 25 30 35

10. In a carburetor of the character described the combination of a reservoir to receive a liquid fuel; reciprocating means

In testimony whereof I affix my signature.

HERMAN A. FINKE.
